UNITED STATES PATENT OFFICE.

NORTON A. NEWDICK, OF COLUMBUS, OHIO, ASSIGNEE TO JAMES ELLWOOD JONES, OF SWITCHBACK, WEST VIRGINIA.

LOADING MACHINE.

1,413,129.

Specification of Letters Patent. Patented Apr. 18, 1922.

Application filed May 5, 1919. Serial No. 294,985.

To all whom it may concern:

Be it known that I, NORTON A. NEWDICK, a citizen of the United States, residing at Columbus, in the county of Franklin and 5 State of Ohio, have invented certain new and useful Improvements in Loading Machines, of which the following is a specification.

This invention relates to an improved 10 loading machine adapted for use in mines for the purpose of conveying coal from its original seam to a mine car, whereby the process of mining coal is economically and expeditiously accomplished.

15 The object of the invention resides in the provision of a coal loading machine mounted for pivotal movement on a truck structure, whereby the gathering mechanism of said machine may be caused to sweep horizontally over a mine floor in order to be kept 20 in constant engagement with the coal to be loaded, said truck structure embodying improved features of construction and operation which enable the gathering mechanism 25 to be conveniently controlled when loading coal and also when in an inoperative position to be readily transported from place to place within a mine.

Another object of the invention resides 30 in equipping the truck structure with ordinary rail engaging wheels which are rotatably connected with the drive motor of the structure so that when the machine is upon a trackway its propulsion through a mine may 35 be easily effected, and to provide the truck structure with a co-operating caterpillar drive, which is capable of being shifted from inactive to active positions so as to relieve said wheels of the weight of the machine, 40 whereby the latter may be employed in scenes of activity wherein the presence of a track way is eliminated, thus enabling the machine to assume any desired position with relation to a face of coal in order that its 45 gathering mechanism may be operated to gain its maximum efficiency, and to render said machine readily operative without the use of a trackway and under adverse working conditions.

50 A further object of the invention resides in the specific construction of the truck structure wherein is provided a set of track engaging wheels, a co-operative caterpillar driving mechanism, and a motor common 55 for driving purposes to both the wheels and to the caterpillar mechanism, clutch means

being provided for connecting the motor for driving purposes with both the wheels and said mechanism when one or the other is in active operation, and to provide a controlling structure for shifting the caterpillar mechanism from its inactive to active positions, said latter structure being operated through the instrumentality of said motor.

With these and other objects in view as 60 will appear as the description proceeds, the invention accordingly consists in the novel features of construction, combination of elements, and arrangement of parts hereinafter to be more fully described and having the 65 scope thereof defined in the appended claims.

In the accompanying drawings:

Figure 1 is a side elevation of a loading machine, showing the application of the improved truck structure comprising the present invention thereto, the caterpillar mechanism being shown in its active position.

Figure 2 is a top plan view of the truck structure,

Figure 3 is an end elevation thereof, and 80

Figure 4 is a transverse sectional view taken along the line 4—4 of Figure 2.

Similar characters of reference denote like and corresponding parts throughout the several views of the drawings.

Referring more particularly to the details of the invention, the truck structure A comprising the preferred form thereof is employed in this instance in connection with a coal loading machine 5, of the type disclosed in the co-pending application of James E. Jones, Norton A. Newdick and William E. Moody bearing Serial Number 302,914 filed June 9, 1919. The machine 5 preferably consists of an elongated frame or body 6, which is provided with a depressed forward end or nose 7, an inclined intermediate portion 8 and an elevated substantially horizontal rear or delivery end 9. This frame or body also carries an endless gathering structure 10, which is disposed to operate on planes parallel to the portions 7, 8 and 9 and may be suitably driven. The nose 7 of the frame is, in practice, driven into engagement with a broken face of coal, 100 so that the gathering structure may then be placed in operation to gather and convey the coal to the delivery end 9, from which point it may be conveyed or discharged into a collecting mine car. Hitherto, it has been 105 the common practice to mount the machine 5 upon a truck provided with wheels dis-

posed for engagement with a trackway, whereby the machine has been rendered transportable and capable of guiding manipulation. However, this structure has had 5 the disadvantage of rendering the machine unwieldy, particularly when the same has been engaged in loading operations, owing to the fact that a trackway had to be laid as the machine was forced farther and farther into the bed of coal, and also its operation in relatively wide rooms or entries was somewhat limited to the arc of swinging movement of which the trackway formed a center. Therefore, it is one of the aims of 10 15 the present invention to mount the machine upon a truck of such construction as to enable the gathering mechanism 10 to have a relatively wide scope of action, to assume any desired angular position and in general 20 to have a greater range of movement when engaged in the process of coal loading, and to combine these advantages with the usual wheel construction which enable the machine to be readily transported.

25 To this end, the truck structure A preferably consists of a frame 11, the latter being provided with the usual journal boxes in which are rotatably mounted the ends of a pair of axles 12, these axles being provided 30 with the usual fixed track engaging wheels 13, disposed to operate over a trackway 14, said wheels serving in connection with the axles 12 to support the frame 11 in the usual manner. The frame 6 is, in turn, pivotally 35 connected with the structure A by means of a pedestal 15, which has its lower ends secured to the substantially center portions of the frame 11 and is formed to provide a curved upper surface 16, the latter carrying 40 guide brakes 17 which are adapted to receive a similar member 18 depending rigidly from the under surface of said body. Through the use of this construction the frame 6 may be swung laterally with respect 45 to its mounting or support, and also the weight of said frame 6, owing to the central location of the pedestal 15, will be equally distributed upon the axles 12, thus preventing excessive wear upon any certain part of 50 the structure A.

The frame 11 is provided with a pair of fixed, parallel and transversely extending supporting bars 19, upon which is mounted in any suitable manner the driving motor 20 55 of the structure. This motor is preferably of the reversible electrical type and has its shaft provided with a pinion 21, which is disposed to normally mesh with an enlarged spur gear 23 fixed to a counter shaft 24, this 60 shaft being mounted for rotation within suitable bearings 25 carried by cross bars 26 which, in turn, are connected with the parallel bars 19.

To couple the motor 20 with the wheels 65 13, so that the machine 5 may be operated

over the trackway 14, said shaft 24 is provided with a slideable clutch 27, which is keyed or otherwise slidably secured for rotation with said counter shaft. This clutch 27 is designed for engagement with a similar face 28 formed on a sprocket wheel 29, the latter being loosely mounted upon the shaft 24. The clutch 27 may be operated through the agency of a forked lever 30, which is pivotally mounted as at 31 upon one of the cross bars 26. The free end of the lever 30 is movably connected with a transversely extending actuating rod 32, the latter protruding outwardly to a point adjacent to the frame 6, whereby an operator 80 by grasping the actuating extremity of the rod 32 may readily rock the lever 30 so as to shift the clutch 27 into or out of engagement with the clutch face 28 of the sprocket wheel 29, thereby controlling the rotation of 85 said sprocket 29 with reference to the counter shaft 24. The rear axle 12 is in this instance provided with a fixed sprocket 33, over which an endless chain 34 is trained, said chain being disposed to also pass over the sprocket 29, whereby when the latter is in rotation movement will be positively imparted to the track wheels 13 so as to effect the propulsion of the truck structure.

As before stated the structure A comprises 90 means whereby the machine 5 may be operated without the use of the trackway 14, and to this end the same is formed to comprise a pair of caterpillars 35 which are capable of being shifted from active to inactive positions or vice versa to control the activities of said machine. In carrying out this idea, the ends of the axles 12 are equipped with eccentrics 36, which are loosely mounted upon said axles, and these 105 eccentrics loosely carry sprocket members 37, over which endless chains 38 are trained, said chains being adapted to carry the usual flexible tread plates 39, whereby upon the rotation of the sprocket members movement 110 will be imparted to said caterpillars as a whole. To govern the positions of the eccentrics 36, the latter are provided with gear segments 40, which are disposed to mesh with co-operative worm gears 41 rotatably 115 carried upon the ends of shafts 42, these shafts being journaled within bearings 43 so as to extend substantially parallel with sides of the frame 11. The intermediate portions of the shafts 42 are provided with 120 fixed worm gears 44, which mesh with co-operative screws 45 formed upon the ends of a transversely journaled shaft 46, the latter being rotatably mounted within bearings 47 mounted upon the side frames 11. Rotation is imparted at predetermined periods to the shaft 46 through the medium of the motor 20, which latter has its counter shaft 24 equipped with a sliding clutch 48, the latter 125 having its positions governed by means of a 130

manually operated rod 49. A sprocket 50 is loosely mounted upon said counter shaft and is provided with a clutch face designed for interlocking co-operation with the clutch 48, whereby when the latter is in engagement with the face of said sprocket 50 the latter will be positively driven as will be clearly understood. A chain 51 connects the sprocket 50 with a similar sprocket 52 mounted upon the shaft 46, whereby when the clutch 48 is properly shifted and motion of the counter shaft 24 will be transmitted to the shaft 46, which in turn being geared to the eccentrics 36 will cause the latter to be operated to position their associated sprocket members 37 either in elevated or lowered positions. When in a lowered position, the caterpillar mechanism 35 will engage with the floor of a mine so as to support the weight of the rear end of the machine 5, and by doing so will eliminate the use of the trackway 14, and when revolved to assume an elevated position, said mechanism 35 will be positioned to permit the loader to be transported about the mine in the usual manner.

Power is imparted to the sprocket members 37 by providing the rear pair of the latter with connected sprocket elements 53, which are disposed to rotate in unison with said members 37, and are also mounted upon the eccentrics 36. Chains 54 are trained over the elements 53 and over similar sprockets 55 rigidly carried upon the ends of a shaft 56, the latter being disposed to extend below and parallel with the counter shaft 24 and is mounted for rotation within bearings provided in the sides of the frame 11. This shaft 56 is provided with an enlarged spur gear 57, which is disposed to mesh with an appreciably smaller pinion 58 loosely mounted upon one end of the counter shaft 24. This pinion 58 is provided with a clutch face disposed for interlocking engagement with a similar face provided on a sliding clutch sleeve 59, the latter being keyed to the end of the shaft 24, and is operated through the agency of a plurality of pivoted manually controlled levers 60. By clutching the pinion 58 in connection with the counter shaft 24, motion will be imparted to the sprockets 55 and thence to the elements 53 which through their connection with the members 37 will effect the operation of the caterpillar mechanism 35 in its entirety.

From the foregoing description taken in connection with the accompanying drawings it will be seen that there is provided improved mechanism for rendering a loading machine readily operative under existing mine conditions. Through the use of the caterpillar mechanism on the structure A the loading machine eliminates to a large extent the use of considerable trackage but when inoperative the same will not interfere

with the rapid transportation of the machine from point to point, which object could not be obtained through the sole use of the caterpillar mechanism as a propelling agent. Again, the mechanism 35 serves to force the forward or nose end 7 of the machine into engagement with the coal pile and maintains this close engagement at all times and owing to its broad tractive grip the same will prevent the machine when under operating conditions from forcing itself away from the coal face. In other words, the caterpillar construction enables the nose end of the machine to be constantly buried under the broken down coal in order that the gathering mechanism may operate with its utmost efficiency. In summary, it will be apparent that an improved truck structure for a loading machine has been provided embodying ordinary track wheels for use in running around a mine and with a co-operative caterpillar drive operable to be thrown into active service when the machine is actively engaged in loading operations. It will of course be apparent that the motor 20 is reversible in order that means may be provided for driving the wheels of a truck either forwardly or backwardly.

What I claim is:

1. A truck comprising a frame, wheeled axles rotatably journaled in connection with said frame, eccentric members loosely carried upon the outer ends of said axles, a chain drive construction loosely mounted upon said eccentric members, means for shifting said members from inactive to active positions to transfer the function of propelling and supporting said truck from the wheels of said axles to said chain elements, and means for selectively rotating said axles or said chain elements.

2. A truck comprising a frame, wheeled axles rotatably journaled within said frame, a motor carried by said frame, clutch means for transmitting the power of said motor to one of said axles to effect the propulsion of said truck over a trackway, means for propelling and supporting said truck independently of said wheels, comprising a plurality of eccentric members loosely mounted upon the ends of said axles, sprocket members rotatably carried in connection with said eccentric members, a pair of flexible driving elements loosely mounted upon said sprocket members, means operated from said motor to rotate said eccentric members to active positions whereby said elements will receive the weight of said truck structure, and clutch means for transmitting the power of said motor to said chain elements to effect the propulsion of said structure when said elements assume active positions.

3. A truck structure comprising a frame, wheeled axles rotatably journaled in con-

nection with said frame, a motor carried by said frame, clutch means between said motor and one of said axles, eccentric members loosely mounted upon the ends of said axles, 5 sprockets loosely mounted upon said eccentric members, driving chain elements trained over said sprockets, means for coupling said sprockets with said motor to effect the propulsion of said elements, adjustable means 10 for shifting said elements from inactive to active positions, comprising toothed segments rotatable in unison with said eccentric members, a worm gearing driven by said motor and meshing with said segments 15 to oscillate said eccentric members from inactive to active positions, whereby the propulsion and support of said structure

may be obtained either through the use of said wheels or said elements.

4. A car embodying therein wheels formed 20 for rail travel; a power plant carried by the car; an elongated endless traction device adapted to travel on the ground; means for moving said elongated endless traction device downward relative to the wheels of the 25 car; means for driving said wheels in either direction from the said power plant; and means for driving said elongated traction device in either direction from said power plant; said wheels being operable independent 30 of said elongated endless traction device.

In testimony whereof I affix my signature.

NORTON A. NEWDICK.
